CLAIM

We claim the ornamental design for a container lid, as shown and described.

DESCRIPTION

FIG. 1 is a top perspective view of a container lid showing our new design; and using the orientation of the image of a bottle as a reference

FIG. 2 is a back right side elevational view thereof;

FIG. 3 is a back left side elevational view thereof;

FIG. 4 is a front right side elevational view thereof;

FIG. 5 is a front left side elevational view thereof;

FIG. 6 is a top plan view thereof; and,

FIG. 7 is a bottom plan view thereof.

The broken lines in the drawings are for illustrative purposes only and form no part of the claimed design.
